REFRIGERATION APPARATUS

Elo C. Tanner, Springfield, Mass., assignor to
Westinghouse Electric & Manufacturing Com-
pany, East Pittsburgh, Pa., a corporation of
Pennsylvania

Application December 2, 1941, Serial No. 421,282

8 Claims. (Cl. 62—141)

This invention relates to refrigeration apparatus and more especially to a draught liquid cooling attachment for a cooler for packaged beverages.

One object of the invention is to provide a draught liquid cooling attachment for a standard cooler for packaged beverages which requires but a minimum of change in the standard cooler when being attached thereto.

A further object of the invention is to provide a draught liquid cooling attachment for a cooler for packaged beverages which attachment substantially decreases neither the storage space of the cooler nor obstructs its access opening.

These and other objects are effected by the invention as will be apparent from the following description and claims taken in connection with the accompanying drawings forming a part of this application, in which

Fig. 1 is a vertical, longitudinal section of a cooler for packaged beverages and the cooling unit for draught liquids installed therein, the section being taken on line I—I of Fig. 2;

Fig. 2 is an end elevation of the packaged beverage cooler and the draught liquid cooler of this invention attached thereto;

Fig. 3 is a section showing somewhat schematically the spout and valve of the draught liquid cooling attachment;

Fig. 4 is an enlarged section on the line IV—IV of Fig. 1;

Fig. 5 is a plan view of the draught liquid cooling unit of this invention; and,

Fig. 6 is an enlarged section on the line V—V of Fig. 1.

Referring now to the drawings for a detailed description of the invention, the standard cooler for packaged beverages will first be described. The reference numeral 10 represents an insulated cabinet embodying a chamber 11 adapted to contain a cooling bath 12 such as water. The entire top of the insulated cabinet 10 is open to provide access to the interior of the chamber 11 and the opening is closed by an insulated cover 13. A heavy sealing gasket 14 is secured to the top edges of the cabinet on which gasket 14 the cover 13 rests.

The cooling bath 12 in the chamber 11 may be cooled by any means and in this embodiment of the invention is shown as being cooled by an evaporative cooling coil 16 which receives liquid refrigerant through a tube 17 from a condenser 18. The condenser 18 is supplied with refrigerant vapor from a compressor (not shown) located in a sealed casing 19. The compressor 55

withdraws the refrigerant vapor from the cooling coil 16 through a suction tube 21.

The cooling unit for draught liquids such as water comprises a catch basin 22 secured by sheet metal screws 23 to one of the top outer edges of the cabinet 10. The catch basin 22 is provided with a drain 20 and with a coupling 25 for attachment to a drain pipe 33. A combined spout and valve unit 24 is secured to the catch basin 22. The spout and valve unit 24 is shown somewhat diagrammatically in Fig. 3 and comprises the spout 26 proper, a valve 27 for admitting and shutting off the supply of water to the spout 26, and a variable restrictor 28 by means of which the maximum flow of the water to the spout 26 can be regulated. The valve 27 is actuated through a valve stem 29 which connects with a spring loaded push button 31.

The valve unit 24 communicates with a pipe 34 which passes sidewardly through a notch 38 in the gasket 14 into the insulated cabinet 10. The pipe 34 then travels downwardly along the wall of the chamber 11 to adjacent the bottom thereof and then horizontally along the bottom of the chamber 11 in a plurality of convolutions 36. The pipe 34 thereupon travels upwardly adjacent the downwardly running portion thereof and emerges from the cabinet 10 through the notch 38 in the gasket 14. The pipe 34 terminates in a coupling 37 by means of which it may be connected to a water supply line 35. The spaces in the notch 38 about the pipe 34 may be filled with a plastic sealing compound 32. The portion of the pipe 34 between the valve unit 24 and the cabinet 10 is preferably surrounded with heat insulation (not shown).

The portion 36 of the pipe 34 which lies convoluted along the bottom of the chamber 11 provides a reservoir for the cooled draught water and likewise provides large heat transfer surfaces for transferring the heat of the water in the convoluted portion 36 to the water bath 12 of the chamber 11. In the embodiment shown, the convoluted portion 36 of the pipe 34 is secured to a cross wire 39 terminating in elevated hooks 39 which hooks 39 may be slipped over the cooling coils 16 for a more permanent interconnection between the two members.

The cooling coils 16 are secured to a spacer 40 which normally rests on the bottom of the chamber 11 when the water cooling unit of this invention is not attached to the beverage cooler but rests on the convoluted portion 36 of the pipe 34 when the water cooling unit is in place.

It will be obvious from the above that the

water cooling unit of this invention may be secured readily to a standard cooler for bottled beverages of the type described. All that is required for such installation is to drill holes for the self-tapping screws 23 and to cut a notch 30 in the rubber sealing gasket 14 for the pipe 34. The cooling coil 16 of the cooler is then bent upwardly, the convoluted portion of the pipe 34 is slipped underneath the cooling coil 16, and the end hooks of the convoluted portion hooked to the cooling coil 16. The cooling unit of this invention is then connected to the water mains and to a waste pipe leading to a sewer and is ready for use. The water cooling unit does not obstruct the access opening of the cooling chamber and does not substantially decrease its storage space for packaged beverages.

While I have shown by invention in but one, form, it will be obvious to those skilled in the art that it is not so limited, but is susceptible of various changes and modifications without departing from the spirit thereof, and I desire, therefore, that only such limitations shall be placed thereupon as are specifically set forth in the appended claims.

What I claim is:

1. In a unit for draught liquids, said unit being adapted for attachment to a cooler for packaged beverages, the combination of a spout, a catch basin connected to said spout to collect liquids issuing therefrom, a drain for said catch basin, a pipe for supplying a liquid to said spout, said pipe having a portion extending sidewardly beyond said catch basin and a downwardly-extending portion at the extending end of said sidewardly-extending portion, a reservoir means at the lower end of the downwardly-extending portion, said reservoir means comprising walls of good heat-conducting material and of relatively large heat-dissipating surfaces and a tube for supplying said reservoir means with a liquid under pressure, said tube having an upwardly-extending portion communicating at its lower end with said reservoir means and a sidewardly-extending portion at the upper end of said upwardly-extending portion and at substantially the same elevation as said sidewardly-extending portion of said pipe.

2. In a unit for draught liquids, said unit being adapted for attachment to a cooler for packaged beverages, the combination of a spout, a catch basin connected to said spout to collect liquids issuing therefrom, a drain for said catch basin, a pipe for supplying a liquid to said spout, said pipe having a portion extending sidewardly beyond said catch basin and a downwardly-extending portion at the extending end of said sidewardly-extending portion, a reservoir means at the lower end of the downwardly-extending portion, said reservoir means comprising walls of good heat-conducting material and of relatively large heat-dissipating surfaces, and a tube for supplying said reservoir means with a liquid under pressure, said tube having an upwardly-extending portion communicating at its lower end with said reservoir means and a sidewardly-extending portion at the upper end of said upwardly-extending portion and at substantially the same elevation as said sidewardly-extending portion of said pipe, said pipe having a valve therein and means within five feet of said spout whereby said valve may be actuated.

3. In a unit for draught liquids, said unit being adapted for attachment to a cooler for pack-

aged beverages, the combination of a spout, a catch basin associated with said spout to collect liquids issuing therefrom, a drain for said catch basin, a pipe for supplying a liquid to said spout, said pipe having a portion extending sidewardly beyond said catch basin, a downwardly-extending portion at the extending end of said sidewardly-extending portion, a reservoir means at the lower end of the downwardly-extending portion, said reservoir means comprising walls of good heat-conducting material and of relatively large heat-dissipating surfaces, a tube for supplying said reservoir means with a liquid under pressure, said tube having an upwardly-extending portion communicating at its lower end with said reservoir means and a sidewardly-extending portion at substantially the same elevation as said sidewardly-extending portion of said pipe, said pipe having a valve therein, means within five feet of said spout whereby said valve may be actuated, and an adjustable restrictor whereby the maximum flow of liquid from said spout may be limited.

4. In a unit for draught liquids, said unit being adapted for attachment to a cooler for packaged beverages, the combination of a spout, a catch basin connected to said spout to collect liquids issuing therefrom, a drain for said catch basin, a pipe for supplying a liquid to said spout, said pipe having a portion extending sidewardly beyond said catch basin, a downwardly-extending portion at the extending end of said sidewardly-extending portion, said downwardly-extending portion being of sufficient length to extend to adjacent the bottom of the packaged beverage cooler to which said unit is adapted to be attached, a convoluted portion lying substantially in a horizontal plane at the lower end of the downwardly-extending portion, said sidewardly-extending portion consisting of good heat-conducting material and having large heat-dissipating surfaces, an upwardly-extending portion at the end of said last-named sidewardly-extending portion, a sidewardly-extending portion at substantially the same elevation as said first-named sidewardly-extending portion, said pipe having a regulating valve therein, a second valve for controlling the maximum flow through the pipes, and means within five feet of said spout whereby said regulating valve may be actuated.

5. In a cooler for draught liquids, the combination of an insulated cabinet embodying a chamber for a refrigerated liquid bath, an access opening in the top of said chamber, a removable cover for said opening, the top of said chamber and the cover, respectively, having sealing edges cooperating with one another, a cooling vessel for draught liquids below the normal liquid level of said bath, inlet and outlet pipes for said cooling vessel, said pipes extending outwardly from said chamber through a notch in at least one of the sealing edges between the cabinet and the cover, said inlet pipe being adapted for connection to a supply of liquid under pressure, a catch basin secured to one side of said cabinet, a spout on said catch basin, said spout communicating with said outlet pipe, and a valve for regulating the liquid flow from said cooling vessel to said spout, said catch basin, spout, cooling vessel, and pipes being removable from said insulated cabinet as a unit.

6. In a cooler for draught liquids, the combination of an insulated cabinet embodying a chamber for a refrigerated liquid bath, an access opening in the top of said chamber, a re-

movable cover for said opening, the top of said chamber and the cover, respectively, having sealing edges cooperating with one another, a cooling vessel for draught liquids below the normal liquid level of said bath, inlet and outlet pipes for said cooling vessel, said pipes extending upwardly along the walls of said chamber and outwardly thereof through a notch in at least one of the sealing edges between the cabinet and the cover, said inlet pipe being adapted for connection to a supply of liquid under pressure, a catch basin secured to one side of said cabinet, a spout on said catch basin, said spout communicating with said outlet pipe, and a valve for regulating the liquid flow from said cooling vessel to said spout, said catch basin, spout, cooling vessel, and pipes being removable from said insulated cabinet as a unit.

7. In a liquid cooler, the combination of an insulated cabinet embodying a chamber for a refrigerated liquid bath, an access opening in the top of said chamber, a removable cover for said opening, a sealing gasket between said cover and the top of said chamber, said gasket having a notch therein, an undulated tube adjacent the bottom of said chamber, inlet and outlet pipes communicating with said tube, said pipes extending outwardly of said chamber through said notch in the sealing gasket, said inlet pipe being adapted for connection to a supply of liquid under pressure, a catch basin secured to one side of said cabinet in a manner not to obstruct said

5 access opening, a spout on said catch basin, said spout communicating with said outlet pipe, and a valve for regulating the liquid flow from said tube to said spout, said catch basin, spout, tube, and pipes being removable from said insulated cabinet as a unit.

8. In a wet cooler for packaged beverages, the combination of an insulated cabinet embodying a chamber for a refrigerated liquid bath, an access opening in the top of said chamber, a sealing gasket substantially surrounding said access opening, said sealing gasket having a notch therein opening upwardly, a container in said chamber below the normal liquid level of said bath, inlet and outlet pipes communicating with said container, said pipes extending outwardly of said chamber through said notch, the end of said inlet pipe being adapted for connection to a water supply system, a catch basin detachably secured to one side of said cabinet in a manner not to obstruct said access opening, a spout on said catch basin, said spout communicating with said outlet pipe, and a cover for the access opening of said cabinet, said cover resting on said 15 20 25 30 gasket, said catch basin, spout, tube, and pipes forming a unit which is removable as a whole from said cabinet, said cover being adapted to completely close said access opening when said unit is in place and to close said access opening except for said notch when the unit is removed.

ELO C. TANNER.
